INVENTOR

UNITED STATES PATENT OFFICE.

MYRON A. BROWN, OF NEW YORK, N. Y.

SWINGING AND SLIDING DOOR CONSTRUCTION.

Application filed November 28, 1922. Serial No. 603,760.

To all whom it may concern:

Be it known that I, MYRON A. BROWN, a citizen of the United States of America, and residing at New York city, in the county of 5 Kings and State of New York, have invented new and useful Improvements in Swinging and Sliding Door Constructions, of which the following is a specification.

The main object of my invention is to 10 provide a simple, inexpensive, and reliable construction which can be readily installed and easily operated in places where space must be economized.

The door is arranged to swing on a vertical axis and then to slide at right angles to the doorway so as to get it out of the way in the smallest space possible.

Figure 1 is a front view of a construction embodying the improvements of my invention.

Fig. 2 is a vertical sectional view on the line 2—2 of Fig. 1.

Fig. 3 is a horizontal section and plan on the line 3—3 of Fig. 1.

Fig. 4 is an enlarged vertical sectional view showing the upper and lower supports for the door.

Fig. 5 is a perspective view of the lower supporting means.

The door 6 may be of any suitable construction and is provided with a hinge rod 7 which is preferably let into a groove in the inner surface of the door near one edge. This hinge rod may be conveniently held in place by bearing strip members 8—8. At the lower end the hinge rod is guided in the slot 9 of the bearing plate 10 which is mounted in the floor and extends inwardly at an angle to the plane of the doorway. At the 40 upper end the hinge rod is guided in a slot 11 in a stationary part of the structure. A removable member 12 may be provided to permit the upper end of the rod to be readily installed.

The plate 10 is preferably provided with a plurality of anti-friction devices such as rollers 13 supported by lugs 14. The door is supported by these rollers and in order to prevent wear on the door I prefer to provide a metal shoe or plate 15 on the lower edge of the door. This shoe is adapted to be supported and travel on these rollers.

The hinge rod 7 is provided with two pinions 16 and 17 at the top and bottom respectively adapted to mesh with the racks 18 and 19 respectively so that the top and

bottom of the rod will be compelled to move together.

The construction is such that the door can be swung open and closed in the usual manner. When it is desired to push the door out of the way, it is swung to its fullest extent about the hinge rod 7 and then pushed in so that the door travels on the rollers 13, while the ends of the hinge rod are guided at the top and bottom in the slots and the pinions rotate in the racks so as to compel the top and bottom of the door to travel together and prevent binding.

It will be seen that the parts are simple in construction and few in number, and may be readily installed. Furthermore, there are no parts likely to get out of order.

I claim:

1. A swinging and sliding door construction comprising a vertical rod, a pinion thereon near each end thereof, a door, bearing strips securing said rod to said door and permitting rotation about said rod as an axis, a track plate extending at a substantial angle to the doorway and having a guide slot for said rod and anti-friction rollers to carry the lower end of the door, two spaced abutments at the upper end of the door and parallel to the guide slot to guide the upper end of said rod, one of said abutments being removable, a toothed rack parallel with the guide slot and meshing with the lower pinion, and a second rack carried by one of said abutments and meshing with the upper pinion.

2. A swinging and sliding door construction comprising a door having a longitudinal groove in one side near one edge of the door, a hinge rod let into said groove, bearing strips to secure said rod to the door, said door being rotatable about said rod as an axis, a track plate extending at a substantial angle to the doorway and having anti-friction rollers to carry the lower end of the door, two spaced abutments at one end of the door to guide one end of said rod and a guide slot parallel to said abutments to guide the other end of said rod, two pinions mounted on said rod near opposite ends thereof, a toothed rack parallel with the guide slot and meshing with one pinion and a second rack carried by one of said abutments and meshing with the other pinion.

3. A swinging and sliding door construction comprising a door having a longitudinal groove in one side near one edge of the

2

door, a hinge rod let into said groove, bearing strips to secure said door to said rod for rotation about said rod as an axis, a track plate extending at a substantial angle to the doorway and having anti-friction rollers to carry the lower end of the door, one of said rollers abutting the lower edge of and carrying the weight of the door when said rod is at the end of its travel toward the doorway, two spaced abutments at one end of the door to guide one end of said rod and a guide slot parallel to said abutments to guide the other end of said rod, two pinions mounted on said rod near opposite ends thereof, a toothed rack parallel with the guide slot and meshing with one pinion and a second rack carried by one of said abutments and meshing with the other pinion.

4. A swinging and sliding door construction comprising a door having a longitudi-

nal groove in one side near one edge of the door, a hinge rod let into said groove, bearing strips to secure said rod to the door, said door being rotatable about said rod as an axis, a track plate extending at a substantial angle to the doorway and having a guide slot for said rod and anti-friction rollers to carry the lower end of the door, one of said rollers abutting the lower edge of and carrying the weight of the door when said rod is at the end of its travel toward the doorway, two spaced abutments at the upper end of the door and parallel to the guide slot to guide the upper end of said rod, one of said abutments being removable, a toothed rack parallel with the guide slot and meshing with the lower pinion, and a second rack carried by one of said abutments and meshing with the upper pinion.

MYRON A. BROWN.
